UNITED STATES PATENT OFFICE.

EDWARD V. WURTS, OF PITTSBURGH, PENNSYLVANIA, ASSIGNOR TO STEEL UTILITIES,
INCORPORATED, A CORPORATION OF NEW YORK.

METAL-WORKING MACHINE.

1,241,266.

Specification of Letters Patent. Patented Sept. 25, 1917.

Application filed July 10, 1915. Serial No. 39,080.

To all whom it may concern:

Be it known that I, EDWARD V. WURTS, a citizen of the United States, residing at Pittsburgh, in the county of Allegheny and State of Pennsylvania, have invented certain new and useful Improvements in Metal-Working Machines, of which the following is a specification.

The invention relates to metal working machines, and more especially to machines in which structural shapes, or like heavy work are successively traveled and accurately stopped to be punched for rivet holes or like operations, the machine being especially adapted for use in the fabrication of structural shapes. More particularly, the present invention relates to means and mechanisms for accurately stopping heavy shapes with accuracy and precision for widely varying successive distances of travel with the greatest desired degree of closeness of subdivision of distance units, and in connection therewith the invention also relates to devices for automatically controlling the movements of such distance determining devices, such controlling devices including the restoration of the mechanism to an initial or normal position after a distance reading has been effectuated, that is, after a shape has been stopped in accordance with a distance setting. Other objects of the invention will be set forth hereinafter in part, and in part will be obvious herefrom.

The invention consists in the novel parts, arrangements, constructions and improvements herein shown and described.

The accompanying drawings, referred to herein and constituting a part hereof, illustrate one embodiment of my invention, and together with the description serve to explain the principles thereof.

Of the drawings:

Figure 1 is a fragmentary top plan, with parts in section and with parts broken away, of a machine constructed in accordance with the principles of the invention;

Fig. 2 is a vertical transverse section, on an enlarged scale, on the line A—B of Fig. 1;

Fig. 3 is a transverse vertical section, likewise on an enlarged scale, on the line C—D of Fig. 1;

Fig. 4 is a transverse vertical section on the line E—F of Fig. 1, being also on an enlarged scale; and

Fig. 5 is a diagrammatic view of certain mechanisms and wiring relating to the shape stopping and positioning means, and to the means for controlling the positioning means and for restoring it to initial or normal position.

Fig. 6 is a fragmentary sectional view from the lower central part of Fig. 1.

In the machine constructed in accordance with my invention, which is illustrated in the accompanying drawings by way of example, means are provided for traveling the shape α along a horizontal pathway past punching mechanism or like tool equipped means, the location of which tool equipped means is indicated generally by the letter y applied to the housing. In conjunction therewith means are provided for stopping the traveled shape in selected predetermined positions to be punched for rivet holes, said stopping means comprising devices engaging the shape to hold it firmly and accurately and also comprising selective settable means, having settable devices representing distance denominations and distance values in the denominations, such means operating automatically to control the stopping and positioning of the shape α in conformity to the settings made. In accordance with certain features of the invention such selective settings of the mechanism to represent desired distances may be effected automatically by suitable means, such as a distance record sheet.

In the embodied form of mechanism, the shape α rests upon a horizontally arranged series of driven rolls 2, which rolls are carried in bearings 3 mounted upon frames 4. The rolls 2 are driven in a suitable manner, and for this purpose there are provided beveled gears 5 fixed to the respective shafts of the rolls 2, the gears 5 intermeshing with beveled gears 6 fixed upon a shaft 7. The shaft 7 extends longitudinally along the pathway of the shape and is rotatably mounted in bearings 8, which bearings are mounted upon one of the frame members 4. The shaft 7 is driven in a suitable manner, and in accordance with certain features of the invention, the rolls 2 may be started and stopped and correspondingly accelerated and retarded in harmony with the operations of the stopping and positioning means. In the embodied form, a gear wheel 9 is shown fixed upon the shaft 7, said gear wheel inter-

meshing with a pinion 10 on the shaft of a motor 11. The motor may be wound and otherwise arranged and controlled to be stopped and started and accelerated and retarded as desired.

In accordance with certain features of the invention, a member or device traveling in fixed relation to the work is provided with a series of engaging or engageable devices, 10 which are separated or spaced apart in the series by distance units or values, such as feet, said engaging or engageable devices passing into engagement with a normally stationary device, such as a projectable latch 15 after the desired number of feet for the particular distance setting has been traveled or passed by the shape. Further in accordance with certain features of the invention, the engagement of said devices is effected in 20 timed relation, the remainder of the distance reading or setting, that is, the inches and fractions of an inch, or the minor portions or readings of a setting, are effected by the joint movement of said engaged devices. 25 In accordance with certain features of the invention, means are provided which operate automatically and resultantly upon the operation of a keyboard, or under the control of a distance record sheet to make the 30 distance setting, to restore the mechanism to an initial or normal position, and to reverse its direction of movement, and to permit it at the proper time to have the necessary or requisite amount of movement for the set or 35 required distance.

In the embodied form of stopping and positioning means, the shape α engages a head 20 against which head the forward end of the shape α presses as the shape travels 40 along its path. Fixed to the head 20 is a bar or rail 21 extending backwardly alongside the shape α , said rail being guided and supported in a suitable manner. Preferably, the rail 21 rests in a cut-away or de- 45 pressed portion 22 at the end of each of the rollers 2, the depressed portion 22 serving as a support for the rail, and its side walls serving as lateral guides therefor.

The series of engaging devices arranged 50 along the rail 21 are shown in the form of a series of notches 23, arranged at equal distances, preferably one foot apart. The co-operating device comprises a latch 24 mounted in a guideway in a block 25, which 55 block is slidably supported and guided upon the top of one of the frame pieces 4, said block 25 having a flange or flanges 26, formed about the horizontal portions 27 and 28 of the frame member 4 to hold the block 60 25 in alignment and to avoid side play, while permitting free longitudinal sliding movement thereof. The block 25 is provided with an internally screw-threaded aperture, in which works a screw-threaded shaft 29. 65 The shaft 29 is carried in bearings 30, which

bearings are mounted upon the machine frame. Suitable means are provided for keeping the shaft 29 in exact longitudinal alignment, such as shoulders on the shaft working against the bearings 30.

The embodied form of means for causing the latch 24 to engage with the selected notch 23 in the rail 21 in accordance with the particular distance setting comprises a bar 32 extending alongside the path of travel of the shape. The bar 32 is provided with a series of contacts 33, regularly spaced apart, and preferably spaced the same as the notches 23 in the rail 21. The contacts 33 are selectively rendered electrically alive in accordance with the setting of the settable distance means. Interposed between the contacts 33 in the bar 32 are return or circuit closing contacts 34, which operate in a manner later to be more fully explained. 85 Traveling along the side of the bar 32, and over the contacts 33 and 34, is a shoe 35 carried in an extension 36 fixed to the rail 21, and spring pressed by a spring 37 against the surface of the bar 32.

The latch 24 as embodied is electrically operated, and in the present case a solenoid 40 is carried in the block 25, the core 41 thereof being fixed to the latch 24 by a pin 44. A spring 43 acting between the end of the solenoid 40 and the head 42 of the solenoid core keeps the latch 24 normally in retracted position, the energizing of the solenoid moving the latch to engaging position as shown in Figs. 1 and 2.

The major distance, such as feet, being determined by the time of energizing of the latch mechanism, the minor distance, such as inches and sixteenths-of-an-inch is determined or effectuated by measured and controlled rotation of the shaft 29. The shaft 29 being stationary longitudinally, the block 25 will move therealong a distance proportional to the amount of rotation imparted to the shaft 29. The controlling means for this mechanism, acting to cause and control the rotation of shaft 29, comprises a pinion 48 fixed to shaft 29. Intermeshing with pinion 48 is a gear wheel 49, which gear wheel is mounted on a shaft 50. Meshing with gear wheel 49 is a pinion 51 fixed on the shaft of a motor 52, although friction driving devices may be interposed if desired. The shaft 50 is journaled in a bearing 53 at the left hand end thereof in Fig. 1, and at 110 the right hand end thereof it is journaled in a frame member 54.

Sleeved on the shaft 50 is a cylindrical head 56, said head being provided with a series of solenoids 57, being twelve in number as embodied, and corresponding to inches of distance. Fixed to the cores 58 of the solenoids 57, respectively, are pins 59, said pins working longitudinally in apertures in the circular face of the cylindrical head 130

56. The pins 59 are held retracted and their solenoid cores 58 are held decentered by suitable means such as springs 60 suitably mounted in the head 56. When a 5 particular solenoid is energized, its pin 59 is projected, through the centering orifice of the solenoid head. In connection with the gear wheel 49 a stop is provided of suitable form, and as embodied, there is formed in 10 the gear wheel 49 an arcuate slot 62, the end of which serves as a stop engaging a selected projected pin 56.

Extending backwardly along the shaft 50 from the head 56, and integral with or fixed 15 to said head, is a sleeve 63 to which is fixed a circular plate 64, the plate 64 facing closely upon the cylindrical frame member 54. In the plate 64 are a series of arcuate slots 65, corresponding in the present embodiment to the various sixteenths-of-an-inch.

In the cylindrical frame piece 54 are mounted one or more annular series of 20 solenoids 70, said solenoids, like the series 25 57 for the inches, being selectively energized from the keyboard or series of automatic contacts 71. Fixed to the core 72 of each of the solenoids 71 is a pin 73, which pins are longitudinally reciprocable in apertures in 30 the annular face of the frame piece 54. The pins 73 are projectable into and retractable from the arcuate slots 65 in the plate 64.

It will be understood that after the latch 24 has engaged with the selected notch 23 35 in the rail 21, that rotation of the gear 49 as permitted and determined by the settings of the pins 59 and 73 will cause rotation of the shaft 29 and thereby longitudinal travel together of the block 25 and latch 24, and 40 therewith of the rail 23, the head 20 and the shape α to effect the inches and fractions-of-an-inch for completing the set or predetermined distance or measurement. The

machine may be operated upon the system 45 of over-all measurements from the end of the work, which system is in general use. The initial position of the gear 49 and of the plate 64 may be determined by permanently projected pins, or such pins may be 50 wired to be projected at the right time and in proper relation to the other pins.

Referring to the wiring diagram of Fig. 5, a represents a series of contacts or switches which correspond to inches and these contacts are made or closed by the setting of the corresponding stop pins of the series 59, (Figs. 1, 3, 4, 5 and 6). There is a like series of contacts or switches b for the sixteenths of an inch, likewise made or closed 55 by the corresponding stop pins of the series 73 (Figs. 1, 3, 4, 5 and 6) and likewise opened when their pins are restored.

At c is a switch or contact, which may be regarded as a stop contact, and which is 60 closed when the gear 49 and plate 64 and

coöperating devices are at the restored or initial position. Two oppositely acting switches e and g are provided in the circuit for the motor controller, one being in the forward circuit and the other in the reverse 70 circuit, to govern or determine the direction of the motor drive. The switches e and g are reversely or oppositely opened and closed by a solenoid d . At h is a switch controlling both circuits to the motor controller, which 75 switch is controlled by a solenoid j , and k represents the lines to any source of power. At m and n are reversely operating interlocking switches making a holding circuit for the solenoid d . A source of current for 80 the solenoid circuits is shown at p . At F and R are indicated the connections to the motor controller for forward and reverse running.

Considering the machine as at the end of 85 its cycle of operation a new setting is made. Current from p flows through closed contact a and through closed contact b to solenoid j thereby closing switch h . Current from the line k flows through the switch h 90 and through switch g to R , in the motor controller, and the motor 52 reverses, driving the mechanism back to the initial position for the new setting.

At or coincident with the initial position, 95 contact c closes, and current from p flows through contact c and solenoid d , thereby opening switch g and closing switch e , and thereby closing the circuit F on the motor controller, and the motor starts forward. 100 As the machine goes ahead, contact c opens but interlock m having closed, current from p goes through interlock n and interlock m to solenoid d , holding switch e closed for forward running until the reading is completed, that is, the work stopped in position and the punching effected, when the stop pins are released.

Contacts a and b open and allow switches h and e to open, thereby stopping the 110 motor and leaving the mechanism in initial position, to repeat the cycle on the next setting. When the rail 21 advances to a point where trolley shoe 35 meets the live segment 33, the latch 24 sets, and current is 115 also delivered through the contact 34 to the return circuit, closing the switch s in the line of the motor controller for forward running.

The invention in its broader aspects is 120 not limited to the precise form of mechanism shown and described, nor to any precise form, but changes may be made therein within the scope of the accompanying claims, without departing from the principles of 125 the invention and without sacrificing its chief advantages.

What I claim as my invention and desire to secure by Letters Patent is:—

1. A machine for punching structural 130

5 shapes at predetermined points, including in combination punching mechanism, a plurality of engageable devices arranged distance units apart and traveling with the work, a stationary engaging device for engaging with a selected engaging device, and means for causing a further travel of said devices while in engagement to complete the desired travel of the shape.

10 2. A machine for punching structural shapes at predetermined points, including in combination punching mechanism, a plurality of engageable devices arranged distance units apart and traveling with the
15 work, a stationary engaging device for engaging with a selected engaging device, means for causing a further travel of said devices while in engagement to complete the desired travel of the shape and means for
20 timing such engagement to select the engaging device corresponding to the desired distance of travel of the shape.

3. A machine for punching structural shapes at predetermined points, including
25 in combination punching mechanism, a plurality of engageable devices arranged dis-
tance units apart and traveling with the
work, a stationary engaging device for en-
gaging with a selected engaging device, and
30 rotary means for causing a further travel
of said devices while in engagement to com-
plete the desired travel of the shape.

4. A machine for punching structural shapes at predetermined points, including
35 in combination punching mechanism, a plurality of engageable devices arranged distance units apart and traveling with the work, a stationary engaging device and means under the control of a distance record
40 sheet for timing such engagement to select the engaging device corresponding to the desired distance of travel of the shape.

5. A machine for punching structural shapes at predetermined points, including
45 in combination punching mechanism, a plurality of engageable devices arranged distance units apart and traveling with the work, a stationary engaging device for engaging with a selected engaging device, and
50 means under the control of a distance record sheet for causing a further travel of said devices while in engagement to complete the desired travel of the shape.

6. A machine for punching structural shapes at predetermined points, including in combination punching mechanism, a plurality of engageable devices arranged distance units apart and traveling with the work, a stationary engaging device for engaging with a selected engaging device, and rotary means under the control of a distance record sheet for causing a further travel of said devices while in engagement to complete the desired travel of the shape.

65. 7. A machine for punching structural

shapes at predetermined points, including in combination punching mechanism, a plurality of engageable devices arranged distance units apart and traveling with the work, a stationary engaging device for engaging with a selected engaging device, and means for causing a further travel of said devices while in engagement to complete the desired travel of the shape, said means comprising a settable distance determining device. 70 75

8. A machine for punching structural shapes at predetermined points, including in combination punching mechanism, a plurality of engageable devices arranged distance units apart and traveling with the work, a stationary engaging device for engaging with a selected engaging device, and means for causing a further travel of said devices while in engagement to complete the desired travel of the shape, said means comprising a settable distance determining device operating under the control of a distance record sheet. 80 85

9. A machine for punching structural shapes at predetermined points, including in combination punching mechanism, a plurality of engageable devices arranged distance units apart and traveling with the work, a stationary engaging device, means for timing such engagement to select the engaging device corresponding to the desired distance of travel of the shape and means for causing a further travel of said devices while in engagement to complete the desired travel of the shape. 100

10. A machine for punching structural shapes at predetermined points, including in combination punching mechanism, a plurality of engageable devices arranged distance units apart and traveling with the work, a stationary engaging device, means for timing such engagement to select the engaging device corresponding to the desired distance of travel of the shape and means for causing a further travel of said devices while in engagement to complete the desired travel of the shape, said timing means and said means for effecting further travel operating under the control of a distance record device. 110 115

11. A machine for punching structural shapes at predetermined points, including in combination punching mechanism, means for traveling and stopping the shape to be punched at predetermined points, said means including a plurality of engageable devices, an engaging device, and means for selectively causing engagement therebetween, said means including a series of contacts and a traveling circuit controlling device to selectively effect the engagement at the proper engageable device for the desired distance of travel of the shape. 120 125

12. A machine for punching structural 130

- shapes at predetermined points, including in combination punching mechanism, means for traveling and stopping the shape to be punched at predetermined points, said means including a plurality of engageable devices, an engaging device, means for selectively causing engagement therebetween, said means including a series of contacts and a traveling circuit controlling device to 10 selectively effect the engagement at the proper engageable device for the desired distance of travel of the shape and means for effecting additional measured travel of said devices while in engagement to complete 15 the desired distance of travel of the shape.
13. A machine for punching structural shapes at predetermined points, including in combination punching mechanism, means for traveling and stopping the shape to be punched at predetermined points, said means including a plurality of engageable devices spaced apart by distance units and traveling with the shape, a stationary device engageable therewith, a plurality of 20 electrical contacts arranged along the path of travel of the shape, a circuit controlling device traveling with the shape and causing the engagement of the devices for the 25 desired distance of travel of the shape.
14. A machine for punching structural shapes at predetermined points, including in combination punching mechanism, means for traveling and stopping the shape to be punched at predetermined points, said means including a plurality of engageable devices spaced apart by distance units and traveling with the shape, a stationary device engageable therewith, a plurality of 30 electrical contacts arranged along the path of travel of the shape, a circuit controlling device traveling with the shape and causing the engagement of the devices for the 35 desired distance of travel of the shape and settable means for selectively energizing the 40 proper circuits.
15. A machine for punching structural shapes at predetermined points, including in combination punching mechanism, means for traveling and stopping the shape to be punched at predetermined points, said means including a plurality of engageable devices spaced apart by distance units and traveling with the shape, a stationary device engageable therewith, a plurality of 45 electrical contacts arranged along the path of travel of the shape, a circuit controlling device traveling with the shape and causing the engagement of the devices for the 50 desired distance of travel of the shape and a distance record sheet controlling the energizing of the proper circuits.
16. A machine for punching structural shapes at predetermined points, including in combination punching mechanism, means for traveling and stopping the shape to be 55 punched at predetermined points, said means including a bar extending along and traveling with the shape and provided with a plurality of spaced engageable devices, a stationary interponent beside the path of travel of the shape, and means for causing the engagement of the interponent with a selecting one of the passing engageable devices, said stationary engaging device stopping the work by its engagement with the selected traveling engageable device.
17. A machine for punching structural shapes at predetermined points, including in combination punching mechanism, means for traveling and stopping the shape to be punched at predetermined points, said means including a bar extending along and traveling with the shape and provided with a plurality of spaced engageable devices, a stationary interponent beside the path of 60 travel of the shape, and means including a series of electrical contacts arranged along the path of travel of the shape and a shoe traveling with the shape for causing the engagement of the interponent with a selecting one of the passing engageable devices.
18. A machine for punching structural shapes at predetermined points, including in combination punching mechanism, means for traveling and stopping the shape to be punched at predetermined points, said means including a bar extending along and traveling with the shape and provided with a plurality of spaced engageable devices, a stationary interponent beside the path of 65 travel of the shape, and means including a series of electrical contacts arranged along the path of travel of the shape and a shoe traveling with the shape and a distance record device selectively energizing said contacts for causing the engagement of the interponent with a selecting one of the passing engageable devices.
19. A machine for punching structural shapes at predetermined points, including in combination punching mechanism, means for traveling and stopping the shape to be punched at predetermined points, said means including a bar extending along and traveling with the shape and provided with a plurality of spaced engageable devices, a stationary interponent beside the path of 70 travel of the shape, and means including a distance record device for causing the engagement of the interponent with a selecting one of the passing engageable devices, said stationary engaging device stopping the work by its engagement with the selected traveling engageable device.
20. A machine for punching structural shapes at predetermined points, including in combination punching mechanism, means for traveling and stopping the shape to be punched at predetermined points, said means including a head engaging the front 75

- of the shape and an attached bar extending along and traveling with the shape and provided with a plurality of spaced engageable devices, a stationary interponent beside the 5 path of travel of the shape, and means for causing the engagement of the interponent with a selecting one of the passing engageable devices.
21. A machine for punching structural shapes at predetermined points, including in combination punching mechanism, a plurality of engageable devices arranged distance units apart and traveling with the work, a stationary engaging device for engaging with a selected engaging device and means including a rotary translational device for imparting longitudinal movement to the engaged devices to complete a desired distance of travel of the shape.
22. A machine for punching structural shapes at predetermined points, including in combination punching mechanism, a plurality of engageable devices arranged distance units apart and traveling with the 10 work, a stationary engaging device for engaging with a selected engaging device and means including a rotary translational device and a distance determining device cooperating therewith for imparting longitudinal movement to the engaged devices to complete a desired distance of travel of the shape.
23. A machine for punching structural shapes at predetermined points, including in combination punching mechanism, a plurality of engageable devices arranged distance units apart and traveling with the work, a stationary engaging device for engaging with a selected engaging device, a 15 screw threaded shaft upon which said engaging device is mounted and distance determining means controlling the amount of rotation of the shaft to complete a desired distance of travel of the shape.
24. A machine for punching structural shapes at predetermined points, including in combination punching mechanism, means for traveling and stopping the shape to be punched at predetermined points, said 20 means including an interponent, a member traveling with the shape and engaged by the interponent, a screw threaded shaft with which said interponent engages, and means for controlling the rotation of said shaft to give measured longitudinal movement to the interponent.
25. A machine for punching structural shapes at predetermined points, including in combination punching mechanism, means for traveling and stopping the shape to be punched at predetermined points, said 25 means including an interponent, a member traveling with the shape and engaged by the interponent, a screw threaded shaft with which said interponent engages, a rotatable, slotted disk connected to rotate with said shaft, distance representing pins controlling the rotation of said disk.
26. A machine for punching structural shapes at predetermined points, including in combination punching mechanism, means for traveling and stopping the shape to be punched at predetermined points, said means including an interponent, a member traveling with the shape and engaged by the interponent, a screw threaded shaft with which said interponent engages, means for controlling the rotation of said shaft to give measured longitudinal movement to the interponent, said means including a plurality of settable devices representing distance values controlling said rotatable member and thereby the longitudinal movement of said interponent.
27. A machine for punching structural shapes at predetermined points, including in combination punching mechanism, means for traveling and stopping the shape to be punched at predetermined points, said means including an interponent, a member traveling with the shape and engaged by the interponent, a screw threaded shaft with which said interponent engages, means for controlling the rotation of said shaft to give measured longitudinal movement to the interponent, said means including a plurality of settable devices representing distance values controlling said rotatable member and thereby the longitudinal movement of said interponent and a distance record sheet.
28. A machine for punching structural shapes at predetermined points, including in combination punching mechanism, means for traveling and stopping the shape to be punched at predetermined points, said means including an interponent, a member traveling with the shape and engaged by the interponent, a rotatable device and connections therefrom to the interponent, and a plurality of settable devices representing distance values controlling said rotatable member and thereby the longitudinal movement of said interponent and a distance record sheet.
29. A machine for punching structural shapes at predetermined points, including in combination punching mechanism, means for traveling and stopping the shape to be punched at predetermined points, said means including an interponent, a member traveling with the shape and engaged by the interponent, a screw threaded shaft with which said interponent engages, a rotatable, slotted disk connected to rotate with said shaft, distance representing pins controlling the rotation of said disk.
30. A machine for punching structural shapes at predetermined points, including in combination punching mechanism, means for traveling and stopping the shape to be punched at predetermined points, said means including an interponent, a member traveling with the shape and engaged by the interponent, a rotatable device and connections therefrom to the interponent, and a plurality of settable devices representing distance values controlling said rotatable member and thereby the longitudinal movement of said interponent.

punched at predetermined points, said means including an interponent, a member traveling with the shape and engaged by the interponent, a screw threaded shaft with 5 which said interponent engages, a rotatable, slotted disk connected to rotate with said shaft, distance representing pins controlling the rotation of said disk and a distance record sheet controlling the setting of said 10 pins.

31. A machine for punching structural shapes at predetermined points, including in combination a punching mechanism, a series of driven rolls for traveling the shape past 15 the punch, a head with which the punch engages, a bar extending from said head along the shape and having a plurality of engaging devices spaced at distance units therealong, a normally stationary interponent 20 adapted to engage with a selected engaging device, and means for controlling said interponent.

32. A machine for punching structural shapes at predetermined points, including in combination a punching mechanism, a series 25 of driven rolls for traveling the shape past the punch, a head with which the punch engages, a bar extending from said head along the shape and having a plurality of 30 engaging devices spaced at distance units therealong, a normally stationary interponent adapted to engage with a selected engaging device, means for controlling said 35 interponent including a distance record sheet.

33. A machine for punching structural shapes at predetermined points, including in combination a punching mechanism, a series of driven rolls for traveling the shape 40 past the punch, a head with which the punch engages, a bar extending from said head along the shape and having a plurality of 45 engaging devices spaced at distance units therealong, a normally stationary interponent adapted to engage with a selected engaging device, and settable means for controlling 50 said interponent.

34. A machine for punching structural shapes at predetermined points, including 55 in combination a punching mechanism, a series of driven rolls for traveling the shape past the punch, a head with which the punch engages, a bar extending from said head along the shape and having a plurality of 60 engaging devices spaced at distance units therealong, a normally stationary interponent adapted to engage with a selected engaging device, and means for imparting measured movement to said interponent 65 after engagement to complete the desired travel of the shape.

35. A machine for punching structural shapes at predetermined points, including in combination a punching mechanism, a series 70 of driven rolls for traveling the shape

past the punch, a head with which the punch engages, a bar extending from said head along the shape and having a plurality of 75 engaging devices spaced at distance units therealong, a normally stationary interponent 80 adapted to engage with a selected engaging device, and means for imparting measured movement to said interponent after engagement to complete the desired travel of the shape including a distance record device.

36. A machine for punching structural shapes at predetermined points, including in combination a punching mechanism, a series of driven rolls for traveling the shape 85 past the punch, a head with which the punch engages, a bar extending from said head along the shape and having a plurality of 90 engaging devices spaced at distance units therealong, a normally stationary interponent adapted to engage with a selected engaging device, and a rotatable screwshaft connected with the interponent, and means for controlling the rotation of the shaft to 95 impart measured longitudinal movement to the engaged interponent.

37. A machine for punching structural shapes at predetermined points, including in combination a punching mechanism, a series of driven rolls for traveling the shape 100 past the punch, a head with which the punch engages, a bar extending from said head along the shape and having a plurality of 105 engaging devices spaced at distance units therealong, a normally stationary interponent adapted to engage with a selected engaging device, a rotatable screwshaft connected with the interponent, and means for controlling the rotation of the shaft to 110 impart measured longitudinal movement to the engaged interponent including a plurality of settable, distance representing devices.

38. A machine for punching structural shapes at predetermined points, including in combination a punching mechanism, a series 115 of driven rolls for traveling the shape past the punch, a head with which the punch engages, a bar extending from said head along the shape and having a plurality of 120 engaging devices spaced at distance units therealong, a normally stationary interponent adapted to engage with a selected engaging device, and a rotatable screwshaft connected with the interponent, and means for controlling the rotation of the shaft to 125 impart measured longitudinal movement to the engaged interponent including a plurality of settable, distance representing devices and a distance record sheet.

39. In a distance determining device for 125 a metal working machine, a plurality of engageable devices traveling with the work, an interponent, and its carrier, a guide therefor, a screw threaded shaft upon which the interponent guide is mounted, and means 130

for controlling the rotation of said screw shaft.

40. In a distance determining device for a metal working machine, a plurality of engageable devices traveling with the work, an interponent, and its carrier, a guide therefor, a screw threaded shaft upon which the interponent guide is mounted, means for controlling the rotation of said screwshaft and means for actuating the interponent.

41. In a distance determining device for a metal working machine, a plurality of engageable devices traveling with the work, an interponent and its carrier, a guide therefor, a screw threaded shaft upon which the interponent guide is mounted, means for controlling the rotation of said screwshaft, means for actuating the interponent and a

distance record sheet controlling said two last-mentioned means.

42. In a distance determining device for a metal working machine, a plurality of engageable devices traveling with the work, an interponent and its carrier, a guide therefor, a screw threaded shaft upon which the interponent guide is mounted, and means for controlling the rotation of said screwshaft including a plurality of settable devices representing distance values.

In testimony whereof, I have signed my name to this specification, in the presence of two subscribing witnesses.

EDWARD V. WURTS.
